United States Patent Office.

D. A. SMITH, OF POMEROY, OHIO.

Letters Patent No. 69,264, dated September 24, 1867.

IMPROVEMENT IN STRAW-CUTTER.

The Schedule referred to in these Letters Patent and making part of the same.

TO ALL WHOM IT MAY CONCERN:

Be it known that I, D. A. SMITH, of Pomeroy, in the county of Meigs, and State of Ohio, have invented a new and improved Fodder-Cutter; and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

This invention relates to a new and improved fodder-cutter, of that class which have the cutters or knives attached to a wheel, which serves the office of a fly as well as that of a cutter-wheel.

The invention consists in a novel construction and arrangement of the parts, as hereinafter fully shown and described, whereby a very superior machine of the kind specified is obtained. In the accompanying sheet of drawings—

Figure 1 is a side view of my invention.

Figure 2 a plan or top view of the same.

Figure 3 a transverse vertical section of the same taken in the line $z z$, fig. 1.

Similar letters of reference indicate like parts.

A represents the feed-box, in which the substance to be cut is placed. This feed-box is supported at a suitable height by any proper framing. B represents a horizontal shaft, the bearings a of which are attached to the framing, at such points that said shaft will be at the lower part of the outer side of the feed-box. This shaft B has a fly-wheel, C, firmly secured on its front end, and to this wheel there is secured a series of knives or cutters, D, which extend from the hub a to the rim b of the wheel, and have a tangential position with the hub, so that they will pass with a drawing cut over the leger-blade e at the front or discharge end of the bottom of the feed-box. The shaft B has a bevel-wheel, E, keyed firmly upon it, and this wheel E gears into a corresponding wheel, F, at the lower end of a vertical shaft, d , on which, above the wheel F, there is a long wheel, e , into which a wheel, G, on a shaft, H, gears. The shaft H has its bearings in uprights I I, the edges of which are bevelled to fit into bevelled grooves in the inner surfaces of the sides of the feed-box, and these uprights, and consequently the shaft H and wheel G, are allowed to rise and fall freely. The feed-roller J also has its bearings in the uprights I I, the feed-roller of course being within the feed-box and a short distance from the discharge end of the feed-box. This feed-roller is rotated by a pinion, K, from the shaft H, said pinion gearing directly into the flutes of the roller, as shown clearly in fig. 3.

From the above description it will be seen that as the wheel C is turned the knives or cutters D will pass over the leger-blade e , at the discharge end of the feed-box, and cut the fodder, while the latter is fed to the knives or cutters by the roller J, operated from the shaft B through the medium of the gearing E F e G and K. And it will further be seen that the feed-roller J is allowed to rise freely to conform to the inequalities of the thickness of the layer of fodder being cut, in consequence of the feed-roller having its bearings in the sliding uprights I I, and the wheel G gearing into the long pinion or wheel e , the length of the latter pinion admitting of a great vertical adjustment of the wheel G without affecting or disarranging the gear in any way, the feed-roller J working equally well under any position of the wheel G within the scope of its vertical adjustable movement.

I do not claim broadly a rotary cutting-wheel provided with knives or cutters to work over the mouth or discharge end of the feed-box of a fodder-cutter, for that is an old and well-known cutting device for the purpose, but I do claim as new, and desire to secure by Letters Patent—

The wheel C, provided with the knives or cutters D, in combination with the feed-roller J, fitted within the sliding uprights I I in the feed-box A, and operated from the cutter-wheel shaft B, through the medium of the gearing E F e G and K, all arranged substantially in the manner as and for the purpose set forth.

D. A. SMITH.
